UNITED STATES PATENT OFFICE

HARRY C. DREIBUSS AND GEORGE S. CHILES, OF ST. LOUIS, MISSOURI, ASSIGNEES TO SCULLIN STEEL CO., OF ST. LOUIS, MISSOURI, A CORPORATION OF DELAWARE

REINFORCED TRUCK BOLSTER

Application filed April 14, 1930. Serial No. 444,180.

This invention relates to truck bolsters, and is illustrated as embodied in a box type of bolster having cross reenforcing members generally of tubular shape which are in effect continuations of flanges about holes in the walls which they brace.

It has been found that bolsters constructed according to former practices do not perform as a true beam and that each wall is distorted beyond the expected deflection under load. For example, with one type of bolster it was found that under severe excess load the top wall or compression member would buckle at about the position of the line 4—4 in Figure 2. This buckling generally took the form of a caving in of the transverse center portion of the wall. At the same time, the side members were pushed outwardly at their centers. By careful measurements, it was found that even under small and normal loads there occurred a certain amount of undesirable breathing or bulging at the sides. Though it has formerly been proposed to provide ribs or webs within truck bolsters, such ribs have never been found thoroughly satisfactory partly because of not being located at the proper place and partly because of the poor foundry practice attending their use since they involved undesirable intersecting walls.

One object of the invention is to provide stronger bolsters for a given weight of metal.

Another object is to provide a bolster in which the stresses more nearly correspond to those in a true beam.

An additional object of the invention is to provide a box type of bolster in which the various sides are reenforced, tied or supported by members which are formed integral therewith without being objectionable to good foundry practice, and especially having as few intersecting walls as possible.

Other objects of the invention will appear from the following description, drawings and claims.

In the drawings, in which like numerals are used for similar parts throughout—

Figure 1 is a plan view of a little more than half of a bolster, it being understood that the other half is identical therewith, as is the case of all the similar figures;

Figure 2 is a vertical longitudinal section of the bolster shown through the line 2—2 of Figure 1;

Figure 3 is a section taken on the line 3—3 of Figure 1 through the center of the bolster; 55

Figure 4 is a section taken on line 4—4 of Figure 2;

Figure 5 is a section taken on the line 5—5 of Figure 2 through the side bearing;

Figures 6, 7, 8, 9 and 10 are corresponding 60 views of a modified form of truck bolster;

Figure 11 is a plan view of a modified end construction which can be used with either of the bolsters of Figures 1 to 10;

Figures 12 and 13 are cross-sections taken 65 on the lines 12—12 and 13—13 respectively of Figure 11;

Figure 14 is a plan view illustrating an additional modification which may be used in either of the bolsters, and also illustrating 70 the relation of such a bolster to the brake apparatus;

Figure 15 is a section taken along the line 15—15 of Figure 14; and

Figure 16 is a partial longitudinal section 75 through the line 16—16 of Figure 15.

Figure 17 is a section, corresponding to Fig. 9, of a further modification of the bolster.

Each of the bolsters embodying this invention includes a center plate 10 which is adapted to pivotally support a car, spring seats 12 upon which the bolster in turn rests, and side bearings 14 which will limit the rocking of the car with respect to the bolster and take varying portions of the load. As is customary, the box type bolster includes a top wall or compressional member 16, of which the center plate and side bearings are 85 parts; a bottom wall or tensional member 18 which includes the spring seat, and two side walls 20 and 22 which act as compressional and tensional members with respect to horizontal loads transverse of the bolster and 90 act as shear plates with respect to vertical loads.

As described above, it has been found that previous forms of bolsters did not support their loads with uniform deflection but that 100

the sides would bulge and the top walls would tend to buckle or cave in along the center.

One manner of overcoming these difficulties has been illustrated in Figure 1, in which tubular cross-members are shown. Thus a tubular member 24 has been located at the former buckling point and extends between the upper or compressional member and the lower or tensional member. This of course would add to the vertical strength of that portion of the upper member the additional vertical strength of the same portion of the lower member. There has in addition been provided a horizontal cross-member 26, also in the form of a tube, which is integral with tube 24. This cross-member 26 not only ties the sides against spreading but acts as a beam to transmit to the sides the load which tends to buckle the top. Thus the upper half of the tube 24 acts as a column resting upon the horizontal tube or beam 26. Wherever possible, intersections in the main walls of the bolster are avoided. Thus instead of having the tubular column-member 24 intersect with a solid top, the tube is made as a continuation of the metal in the top wall, that is, it has a non-intersecting reentrant junction with said wall. It is thus in the nature of a flange surrounding a hole in the top member and continued down and made integral with a similar flange surrounding a hole in the bottom member. This provides continuous lines of metal which merely curve from the wall into the tube and permit a uniform flow of metal at the corners. This was not possible with the reenforcing web structures heretofore suggested.

The side bearing has been similarly reenforced by means of a tubular column 28 which aids in the support of the side frames and in turn is supported by the tubular beam 30 which is supported by the side walls and which ties said walls into proper relation. As illustrated, the tubular beam or cross-member 30 is formed with the previously described non-intersecting reentrant junctions with said walls 20 and 22, though the tubular column 28 is illustrated as intersecting the side bearing 14. This intersection may be avoided by the formation of a hole in a way similar to that shown in Figure 7. In any event, an additional bearing plate may be attached if desired.

The center plate 10 may be supported by a tubular column 32 which is in turn supported by a tubular cross-shaft or beam 34, which latter is integral with the sides in the same manner as tubular cross-members 26 and 30. A support 36 may be provided to maintain the center pin 38 in proper position. Core support holes of course are provided wherever necessary. For this purpose, the tubes are beneficial as the core support holes may be left through the tubes, or

as pointed out hereinafter, large portions of the tubes may be omitted.

The construction of Figures 6 to 10 is very similar to the foregoing in certain respects; especially it is similar in that the cross-members are partially tubular continuations of the main walls of the bolster instead of webs intersecting with them. Large parts of the tubes however have been done away with. Thus in Figure 10, the horizontal cross-tube 75 has been restricted to a flange 52 around the hole and the narrow portions 54. The tubular column 56 thereabove has been partly cut down to the flange 56 and the portions 58. Below the member 54 there has been provided an additional tie member 60 which is an extension of a portion of the flange 62. Below the member 54 there has been provided an additional tie member 60 which is an extension of a portion of the flange 62. The flange 62 extends around a large hole in the tensional member 18, it having been found that the metal from this hole can thus be saved.

The top wall is braced at its buckling point 90 by the partially cut away column 66 which in this modification is entirely supported by cross-beam 68, which is also reduced to a minimum, and the side walls. The column 66 may be of curved or of flat cross-section. 95

In this embodiment (Figure 6), a slightly different construction of the center portion has been shown in which the tubular column 69 is partially cut away and is supported by the skeleton of the horizontal tubular beam 70. The bottom member of this beam is so located that it may support the center pin. A tube or parts thereof 72 may be provided to properly space the beam 70 and the bolster's bottom wall or tensional member 18. If desired, its junction may also be of the reentrant flange type.

The spring seat is in a similar manner backed up by the vertical tube or column 76 which is integral with a beam or horizontal tube 78. Both of these tubular members may be cut away in part as shown.

A further modification of the spring seat structure is illustrated in Figures 11 to 13, in which there is no cross-tube, the vertical tube portion or flange 80 having extension 81 joined to the top member of the bolster. It is noted in all of these end constructions, the reenforcing members have the preferred continuous line non-intersecting reentrant junction with the walls to which they are connected. Obviously either one of these end constructions may be used with either of the bolsters of Figure 1 or Figure 6.

Wherever the cross-members herein described are used, the unnecessary parts of metal may be omitted in casting to decrease the amount of metal used. Where a part is cut away in this manner, the most effective part of course is retained. Thus in Figure 130

10 the side portions 54 of the cross-beam are retained, each side portion being more effective as a beam than would be either the top or bottom portion, and just as effective as a tie member. Also, it is noted that the portion 58 of the vertical column extending from said beam is of greater curvature, thus increasing its strength as a column.

In Figures 14 to 16 are illustrated certain modifications which may be used with any previously described modifications. It is sometimes desirable to have the brake rods located above the bottom of the truck bolster and to have the connecting rod 82 extend 15 through the bolster. This adds an element of safety to the brakes in case of disconnection or breakage of some parts. In order to better provide for this arrangement of brake rods, tubular passages transverse of the bolster may be provided. Although only one is necessary, two are provided in order to avoid 20 having right and left sides of the bolster. These passages are provided by a formation of holes having tubular flanges 83, continued 25 as cross-members 84, integral with the sides of the bolster in the same manner as described in connection with other figures, that is, these pipes are in the nature of extended flanges around the holes in the sides. The tubes 30 therefore perform the additional function of tying the sides and of serving as beams to give additional support to the center plate 10 through the legs 85 forming extensions of the tubular flanges 86. Two of the legs 35 85 are provided with extensions 88 which may intersect with the bottom of the bolster, or may join therewith in continuous lines.

If desired, the bolster may be made a little deeper, that is, of a little larger size from 40 top to bottom for additional strength. In that event, the spring plank 90 will be somewhat lowered in the middle, as indicated. The spring plank 90 is otherwise of the usual form.

45 It is to be understood that many other embodiments of the invention, including some in improved form, will be apparent and in the course of time will be devised by those skilled in the art. Our invention includes all of these which come within the spirit of the following claims, construed as broadly as the prior art will permit.

We claim:

- 50 1. A truck bolster including a compressional member, a tensional member, and a reinforcing member integral therewith comprising a portion of a tube with the remainder of the tube cut away.
- 55 2. A truck bolster including a compressional member, and a tensional member, one of said members having a hole therethrough and having a flange curving toward the other of said members at the edge of said hole, the flange being extended and integrally connected to said other member.

3. A truck bolster including a compressional member, and a tensional member, each of said members having a hole therethrough and each having a flange curved toward the other around the edge of said hole, the flanges being extended and integrally connected to each other. 70

4. A truck bolster comprising a hollow casting, a partially tubular reinforcing member integral with opposite sides of said hollow casting, a partially tubular member integral with a third side of said casting, said partially tubular members being rigidly connected and in substantially the same transverse planes. 75

5. A truck bolster comprising a hollow casting, a partially tubular reinforcing member integral with opposite sides of said hollow casting, a partially tubular member integral with a third side of said casting, said partially tubular members being rigidly connected and in substantially the same transverse planes, one of the partially tubular members having a non-intersecting junction with the side of the hollow casting. 85

6. A truck bolster of the box type including an upper compressional member, a curved cross-sectioned column supporting its transverse center, and a beam supporting the foot of said column and supported by the sides. 90

7. A truck bolster of the box type including an upper compressional member, a curved cross-sectioned column supporting its transverse center, and a beam supporting said column and supported by the sides, said beam in part being tubular and being a substantial continuation of the side portions. 100

8. A truck bolster of the box type including an upper compressional member, a column supporting its transverse center, and a beam supporting said column and supported by the sides, the center of said column passing through the cross-sectional limits of said beam. 105

9. A truck bolster of the box type including spaced columns supporting the transverse center of the upper wall, and a curved cross-sectioned beam supporting each of said columns and supported by the side walls of the bolster. 110

10. A truck bolster of the box type including an upper compressional member having a side bearing portion, a column supporting its transverse center and a curved cross-sectioned beam supporting said column and supported by the side walls of the bolster. 120

11. A truck bolster of the box type including at least four spaced tie members extending between the side walls at about their vertical centers and formed integral therewith for minimizing the breathing of said walls, said tie members being at least partially tubular and joining the side walls in the form of reentrant flanges thereon. 125

12. A truck bolster of the box type includ- 130

- ing at least four spaced tie members extending between the side walls at about their vertical centers and formed integral therewith for minimizing the breathing of said walls,
5 said tie members being at least partially tubular and joining the side walls in the form of reentrant flanges thereon, and vertical columns supported thereby and supporting the transverse center of the upper wall.
- 10 13. A truck bolster of the box type including a center plate, side walls and a bottom, said side walls each having a hole therethrough near said center plate through which a brake rod may pass and of sufficient size to permit the necessary relative movement between the brake rod and the bolster, a flange at the edge of each hole curving toward the other side wall for compensating for the weakening effect of said holes, and
15 integral extensions connecting said flanges.
14. A truck bolster of the box type including a center plate, side walls and inner members for supporting said center plate, said side walls and inner members all having a passage therethrough through which a brake rod may pass and of sufficient size to permit the necessary relative movement between the brake rod and the bolster, and a flange curved from the edge of the opening of said passage
20 in each of said side walls, said inner members forming integral extensions connecting said flanges.
15. A truck bolster of the box type including a center plate, side walls and inner members for supporting said center plate, said side walls and inner members all having a passage therethrough through which a brake rod may pass and of sufficient size to permit the necessary relative movement between the
25 brake rod and the bolster, a flange curved from the edge of the opening of said passage in each of said side walls, and integral extensions connecting said flanges.

45 Signed at St. Louis, Missouri, this 2nd day
of April, 1930.

HARRY C. DREIBUSS.
GEORGE S. CHILES.
